VARIABLE GAIN AMPLIFIER

David J. Miller, Jr., Philadelphia, Pa., assignor,
by mesne assignments, to Philco Corporation,
Philadelphia, Pa., a corporation of Pennsyl-
vania

Application June 28, 1944, Serial No. 542,460

10 Claims. (Cl. 178—7.1)

1 This invention relates to improvements in variable gain amplifiers especially adapted for use in television systems. More particularly the invention relates to improvements in a variable gain amplifier which may be utilized both for blanking out the video signal during the synchronizing or retrace intervals and for "fading" the video signal in or out at will. A variable gain amplifier of this character is disclosed and claimed in U. S. Patent No. 2,233,317, granted February 25, 1941, to P. J. Konkle, and assigned to the assignee of the present application. The present invention is an improvement over that of the said patent.

In the said Konkle patent there is disclosed a blanking out and fading amplifier comprising a balanced circuit arrangement and an associated gain control means for effecting the blanking and fading functions. One purpose of the arrangement is to prevent any transient or other extraneous signal from appearing in the output of the amplifier in response to the blanking and fading functions. While the device is generally satisfactory, the balanced condition of the amplifier may be disturbed when the fading control is actuated, and the presence of the blanking signal during the fading operation has been found to produce undesirable effects. By the present invention this objection is overcome by the provision of means for so varying the amplitude of the blanking signal during the fading operation as to prevent the said signal from deleteriously affecting the operation of the system.

The principal object of the invention, therefore, is to provide an improved blanking out and fading amplifier.

A more specific object of the invention is to provide a novel control means in a blanking out and fading amplifier of the character above mentioned, which control means prevents undesired effects due to the blanking signal during fading.

Other objects and features of the invention will be apparent from the following description in conjunction with the accompanying drawing, in which:

Fig. 1 is a schematic illustration of a dual channel television transmission system to which the present invention may be applied; and

Fig. 2 is a circuit diagram of a preferred form of the blanking out and fading amplifier provided by this invention.

To facilitate a clear and complete understanding of the invention, reference may first be had to Fig. 1. In a conventional television system a video or picture signal is obtained from a camera

2 tube and head amplifier, represented at 11, which signal is transmitted to a blanking out and fading amplifier 12 and is then transmitted to a combining amplifier 13 which also receives the synchronizing signals from source 18. The composite signal is supplied to the modulator and output system 14 connected to the usual antenna 15. The blanking out amplifier 12 receives blanking signals from source 18. In a dual channel system, such as shown in Fig. 1, another camera tube and head amplifier 16 supplies a video signal to a blanking out and fading amplifier 17 which is also connected to the composite signal amplifier 13.

In an arrangement such as has been schematically illustrated in Fig. 1, the video signal may be obtained from one of a plurality of sources, and in order to change from one source to the other, fading control means 19 and 21 are provided to accomplish fading ahead of the composite signal amplifier 13, and the same synchronizing signals are supplied to all of the several camera tubes such as 11 and 16. Thus when a picture signal is faded in or out, transmission of the synchronizing signals is not deleteriously affected and hence the television receivers may be maintained in synchronism with the television transmitter.

In Fig. 2 there is illustrated a preferred form 30 of the blanking out and fading amplifier provided by the present invention, which may be employed in the system of Fig. 1. This device is of the type shown in the above-mentioned Konkle patent, but it embodies the improvements of the present invention. The video signal is supplied through a coupling capacitor 22 to the grid of a vacuum tube 23. A second tube 24 has its grid interconnected with the grid of tube 23 by a grid resistor 25. A suitable source of bias voltage 26 is connected between ground and the grid of tube 24. The tubes 23 and 24 are preferably identical with respect to their electrical characteristics. Both tubes are biased by the voltage of source 26 and the voltage across resistor 27 which is included in a common cathode circuit for the said tubes. The output signal of tube 23 appears across a variable resistor 28 connected between a suitable source of anode voltage 29 and the anode of the tube 23. The signal appearing across the resistor 28 is transferred through a coupling capacitor 31 to the grid of a vacuum tube 32 which is provided with a grid resistor 33 connected to a suitable source of grid bias voltage. The output voltages of the tubes 24 and 32 are combined by virtue of a common anode resistor 34, and the

3

output signal is derived by way of coupling capacitor 35. An inductor 36 preferably is interposed between the common anode resistor 34 and the source of anode potential 29, in order to minimize the effect of the capacity to ground of the coupling condenser and the inter-electrode capacities of the tubes.

The value of the resistor 28 may be so adjusted that the amplification of any video signal through the branch of the amplifier including the tubes 23 and 32 is the same as the amplification of any input signal through the other branch comprising the tube 24 alone. Any output signal from tube 24 will be in opposite phase to the output signal of the first branch including tubes 23 and 32, so that any input signal or voltage variation applied to both of the tubes 23 and 24 produces no resultant output signal.

The amplification or gain of the amplifier may be varied by varying the bias voltage appearing across the common cathode resistor 27. To this end, there is provided a vacuum tube 31 having a cathode circuit which includes the resistor 27. The anode of tube 31 is connected to the anode voltage source 29 through an anode resistor 38 which may be by-passed to ground by a capacitor 39. The blanking out signal may be applied to the grid of the tube 31 through a coupling capacitor 41. The grid circuit of tube 31 includes a grid resistor 42 connected to an adjustable contact of a voltage divider or potentiometer 43 which has one terminal connected to ground and the other terminal connected to the negative side of a suitable source of bias potential. The blanking out signal supplied through the capacitor 41 periodically raises the grid voltage of tube 31 and causes increased flow of current in the cathode circuit, thereby increasing the voltage drop across the resistor 27 and effecting periodic cutoff of tubes 23 and 24. Whenever desired, the video signal may be faded out or in by manipulation of the potentiometer 43 which varies the gain of tubes 23 and 24 by varying the current flow through resistor 27.

The variable gain amplifier as thus far described corresponds substantially to that shown in the aforementioned Konkle patent. Such an amplifier, while generally satisfactory, has a tendency to become unbalanced when the fading potentiometer 43 is operated. It is practically impossible to obtain two tubes, for use as tubes 23 and 24, so closely matched as to maintain a balanced condition for different adjustments of the potentiometer 43, particularly since tube 24 is working into a plate load which is common with tube 32 while tube 23 is working into its own plate load. This difficulty is further aggravated by the fact that tube 23 is coupled to the grid of tube 32 through condenser 31 which removes the D. C. component and causes the signal on the grid of tube 32 to operate about the grid bias level of that tube, whereas tube 24 is D. C. coupled to the output circuit and preserves the D. C. component.

The amplifier may be adjusted, as previously described, for operation with a given setting of the potentiometer 43, and as long as the potentiometer adjustment remains the same, the system will maintain its balanced condition. But when the potentiometer adjustment is varied, e. g. to fade the video signal out, the system tends to become unbalanced for the reasons stated above. If the blanking signal were not present, this would be immaterial, but the presence of

the blanking signal tends to produce undesired output components, whose presence it is the function of the balanced amplifier to prevent. The undesired components tend to distort the video signal during the fading operation, and may even affect the synchronization deleteriously.

In accordance with the present invention, the foregoing objection is overcome by fading out the blanking signal when the potentiometer 43 is operated in a direction to fade out the video signal. To this end there is provided an additional tube 44 having a coupling capacitor 45 connected to the source of blanking out signal. The tube 44 has an anode resistor 46 connected to the source of anode voltage and is coupled to tube 31 through condenser 41. The cathode of tube 44 is connected to ground, and its grid-to-cathode circuit is completed by a grid resistor 47 connected to an adjustable contact on a potentiometer 48 which is connected between a ground and a suitable source of bias voltage. It will be seen that opposite ends of the potentiometers 48 and 43 are connected to ground and that the dotted line representation between the adjustable contacts thereof indicates a common control for the two potentiometers. The tube 44 preferably is a small triode, such as a 6J5G, whereas the tube 31 may be a larger triode, such as a 6AC5-G or a beam power amplifier such as a 6V6. By this arrangement, tube 44 is biased to cut off when potentiometer 43 is operated in a direction to apply a more positive voltage to the grid of tube 31. By careful selection of the values of the potentiometer resistances, the blanking signal may be caused to fade out before it can produce any undesired effect.

When the potentiometer 43 is operated in the opposite direction to fade in the video signal, the blanking signal is also faded in by the potentiometer 48, and when the normal setting of potentiometer 43 is reached the balanced condition of the amplifier is restored.

While for the purpose of illustrating and describing the present invention a certain preferred specific embodiment has been shown, it is to be understood that the invention is not to be limited thereby since such variations are contemplated as may be commensurate with the scope of the appended claims.

50 I claim:

1. In a television system, a video signal amplifier, means responsive to a control signal for varying the gain of said amplifier, manually-operable means for varying the gain of said amplifier from a normal value to substantially zero or vice versa, whereby the video signal may be faded out or in, and means operable conjointly with said last-named means for preventing the control signal from deleteriously affecting the amplifier during the fading operation.

2. In a television system, a video signal amplifier, a control signal source, means responsive to said control signal for varying the gain of said amplifier, manually-operable means for varying the gain of said amplifier from a normal value to substantially zero or vice versa, whereby the video signal may be faded out or in, a vacuum tube interposed between said control signal source and said amplifier, and means for reducing the conductivity of said tube during operation of said manually-operable means to reduce the gain of said amplifier.

3. In a television system, a video signal amplifier, a control signal source, means responsive to said control signal for varying the gain of said

amplifier, a vacuum tube interposed between said amplifier and said source of control signal, and manually-operable means for varying the bias of said vacuum tube and said amplifier to comittantly decrease the amplification of said amplifier and the transmission of said control signal by said vacuum tube.

4. In a video signal amplifier for a television system, an input circuit, an output circuit, video signal amplifying means connected between said input circuit and said output circuit for transferring signals therebetween, means including an auxiliary vacuum tube for controlling the gain of said amplifying means in response to a gain control voltage, said voltage being applied to the input circuit of said tube, a second auxiliary vacuum tube interposed between said first auxiliary vacuum tube and the source of gain control voltage, manually-operable means for variably biasing said first tube to fade the video signal out or in, and means for biasing said second tube substantially to cut-off during the fading out of the video signal.

5. In a television system, a plurality of video channels, an amplifier in each of said channels, means including an auxiliary vacuum tube associated with each of said amplifiers for controlling the gain of the associated amplifiers in response to gain control voltages, means including a second auxiliary vacuum tube interposed between each of said first auxiliary vacuum tubes and the source of gain control voltage, said gain control voltages being applied to the input circuits of the respective second-mentioned auxiliary vacuum tubes, and manually-operable means electrically connected to each of said auxiliary vacuum tubes for concomittantly increasing the conductivity of one of the auxiliary vacuum tubes while decreasing the conductivity of the other of said auxiliary vacuum tubes, whereby the video signal of one channel may be faded out and the video signal of another channel may be faded in.

6. In a television system, a video signal amplifier, a control signal source, vacuum tube means responsive to said control signal for periodically varying the gain of said amplifier, and manually-operable means for varying the gain of said amplifier to substantially zero and vice versa, and for varying the magnitude of the control signal applied to said vacuum tube means to substantially zero and vice versa, whereby the video signal may be faded out and in.

7. A blanking out and fading amplifier for use in a television system, comprising a balanced amplifier circuit constructed and arranged to transfer a video signal and to prevent transfer of other signals or voltage variations, means responsive

to a blanking signal for reducing the gain of said amplifier substantially to zero, manually-operable means for varying the gain of said amplifier so as to fade the video signal out or in, said blanking signal tending to introduce deleterious effects during the fading operation, and means responsive to the fading operation for preventing the blanking signal from introducing such effects.

8. A blanking out and fading amplifier for use in a television system, comprising a balanced amplifier circuit constructed and arranged to transfer a video signal and to prevent transfer of other signals or voltage variations, said amplifier circuit including a pair of input tubes having a common cathode circuit, a resistor in said common cathode circuit, a gain control tube having a cathode circuit including said resistor, means for applying a blanking signal to the grid of said gain control tube so as to reduce the gain of said amplifier substantially to zero, manually-operable means for variably biasing said gain control tube so as to fade the video signal out or in, said blanking signal tending to introduce deleterious effects during the fading operation, and means responsive to the fading operation for preventing the blanking signal from introducing such effects.

9. A blanking out and fading amplifier for use in a television system, comprising a balanced amplifier circuit constructed and arranged to transfer a video signal and to prevent transfer of other signals or voltage variations, said amplifier circuit including a pair of input tubes having a common cathode circuit, a resistor in said common cathode circuit, a gain control tube having a cathode circuit including said resistor, means including another tube for applying a blanking signal to the grid of said gain control tube so as to reduce the gain of said amplifier substantially to zero, manually-operable means for variably biasing said gain control tube so as to fade the video signal out or in, said blanking signal tending to introduce deleterious effects during the fading operation, and means responsive to the fading out operation for biasing said other tube substantially to cut-off so as to prevent the blanking signal from introducing such effects.

10. In a television system, a video signal amplifier, a control signal source, means responsive to said control signal for periodically varying the gain of said amplifier, and manually-operable means for varying the gain of said amplifier to fade the video signal out or in, and for simultaneously varying the magnitude of the control signal so as to prevent deleterious effects by the latter signal during the fading operation.
